UNITED STATES PATENT OFFICE.

WILLIAM A. YOUNG AND ROLAND L. ANKENER, OF NEW YORK, N. Y.

GROMMET-MAKING MACHINE.

Application filed July 25, 1928. Serial No. 295,321.

This invention relates to a grommet making machine, and has for an object to provide an improved construction wherein grommets may be accurately and strongly formed from 5 rope strands at a comparatively high rate of speed.

Another object of the invention is to provide a grommet forming machine wherein the strands are fed into the machine by hand 10 and partly held in place thereby during the forming operation.

A further object of the invention, more specifically, is to provide a grommet forming machine wherein a twisted strand of rope is 15 twisted or entwined while applied to a mandrel and acted on in such a manner that a grommet will be formed thicker than the strands used.

An additional object is to provide a 20 grommet forming machine wherein the grommet is twisted into the desired shape from a strand of rope and discharged with one end loose but in position to be forced between certain twists manually to a tied position.

25 In the accompanying drawings,—

Figure 1 is a front view of a machine disclosing an embodiment of the invention;

Figure 2 is an enlarged fragmentary view 30 partly in section showing the winding structure;

Figure 3 is a top plan view of the principal part of the machine shown in Figure 1;

Figure 4 is a longitudinal vertical sectional view through the machine shown in Figure 1 35 with the winding apparatus omitted;

Figure 5 is a sectional view through Figure 4 approximately on the line 5—5;

Figure 6 is a fragmentary view showing 40 the position of the rollers as the mandrel begins its outward movement;

Figure 7 is a fragmentary perspective view 45 of part of the mandrel shown in Figure 4 with a strand of rope looped thereover.

Figure 8 is a fragmentary view partly in 50 section showing the position of the parts at the beginning of the formation of the grommet;

Figure 9 is a view similar to Figure 8 but 55 showing the parts and the grommet at the end of the forming operation;

Figure 10 is a side view on an enlarged scale of a finished grommet.

Referring to the accompanying drawings by numerals, 1 indicates a support of any kind 55 adapted to carry the various mechanism here-

inafter fully described. Arranged below the support 1 is a floor or second support 2 carrying brackets 3 and 4 in which the rod 5 is journaled. Treadles 6 and 7 are mounted to rock on the rod or shaft 5 and to actuate certain mechanism hereinafter fully described. In making the grommet 8, as shown in Figure 60 10, preferably two strands of rope are taken and doubled and the closed end slipped over the knob 9 (Figure 1). This knob is then rotated until the strands are twisted into the rope or cable 10, said strands being held by a hand, as indicated by dotted lines in Figure 1, until the twisting operation has been completed. As soon as this has been done the 65 looped portion 11 is slipped over the knob 9 and passed over the mandrel 12 (Figure 7) and the free end of the rope 10 is passed through the loop or eye 11. The free end of the rope or cable 10 is retained in the hand 70 and the cable is wound around the mandrel 12, as shown in Figure 8. As the mandrel and certain other parts function the rope or cable is drawn in and twisted, as shown in Figure 9. This completes the grommet except that the 75 free end must be forced through certain turns 8' of the grommet 8, as shown in Figure 10. As soon as the free end has been inserted, as shown in Figure 10, the unnecessary part 80 may be cut off and the grommet is complete. 85 In order to cause the knob 9 to rotate the same is rigidly secured to a shaft 13 which is journaled in suitable bearing members 14 and 15. The friction clutch member 16 is rigidly secured to the rod or shaft 13 and carries a 90 leather or other friction surface 17. A pulley 18 is loosely mounted on the shaft 13, said pulley having a comparatively long hub 19 adapted to bear against the plate 20. A spring 21 acts on the collar 22 adjustably 95 clamped to the rod 13 by a set screw and also on the disk 20 for forcing the pulleys 18 against the friction surface 17. When this has been done power will be transmitted to the clutch 16 and thence to the shaft 13. A 100 lever 23 is pivotally mounted at 24 on a support 25, said lever having an extension 26 positioned to bear against the central part of disk 20. A spring 27 is connected to lever 23 and to the supporting standard 15', said 105 spring being more powerful than spring 21 so as to hold the disk 20 away from hub 19. A cable 28 is connected to lever 23 and extends over the pulley 29 and thence downwardly to the treadle 6. Whenever treadle 6 is moved 110

downwardly cable 28 is pulled and this swings the lever 23 against the action of spring 27, thus permitting spring 21 to function. Immediately upon the release of the disk 20 shaft 13 will begin to rotate at a comparatively high rate of speed and will quickly twist the strands forming the rope 10. As soon as the proper twist has been secured the operator releases treadle 6 and spring 27 quickly overcomes the action of spring 21 and the power is thus quickly removed from shaft 23. The belt 30 extends over the pulley 18 and over a pulley 31 rigidly secured to the power shaft 32, whereby whenever this power shaft is operated, power may be transmitted to shaft 13, as desired. At the same time that the lever 23 is swung by reason of the operation of treadle 6 rod 33 will be pulled by treadle 6 (Figure 1) and the lever 34 will be swung, whereupon the sliding bar 35 will move upwardly. This sliding bar is guided by a suitable guiding structure 36 and carries an L-shaped bracket 37 at its upper end. This bracket in turn carries standard 38 positioned to support the axle or shaft 39 on which the roller 40 is mounted. This roller is grooved, as shown in Figure 1, said groove being almost a half-circle and accommodating the mandrel 12 when the roller is elevated. The upward movement of the roller 40 is sufficient to raise the mandrel 12 to a position in contact with the roller 41 and as this roller is rotating in the direction indicated by the arrow, mandrel 12 will be moved outwardly until the abutment 43 strikes the plate 44, but as the mandrel moves outwardly it will rotate for about a one-quarter revolution by reason of the fact that the shaft 45 is square and is twisted sufficiently to give a one-quarter revolution to the mandrel. The member 46 is provided with a proper opening for receiving the shaft 45. It will thus be seen that the mandrel is forced outwardly at the time that the twist of rope 10 is made. As heretofore set forth, the rope 10 is looped over the mandrel 12 when in its outer position and the free end is held by the hand of the operator as the mandrel is moved inwardly on its return movement. As soon as the treadle 6 has been released, roller 40 and associated parts will immediately move downwardly and the parts will quickly assume the position shown in Figures 4 and 8. The mandrel 12 is tapering for its full length and consequently as the rope 10 is rolled and twisted upon itself until it assumes the position shown in Figure 9, the reduction of the bore of the grommet will be taken care of by the reduction in size of the mandrel as it moves backwardly. The power shaft 32 carries pulleys 47 and 48, pulley 47 accommodating belt 49, which belt fits over the pulley 50. The pulley 48 is of ample width to accommodate the belts 51 and 52, belt 51 passing over pulley 53, while belt 52 passes over pulley 54. Pulley 50 is rigidly

secured to a stub shaft 55 which in turn is rigidly secured to the roller 41, while pulley 54 is rigidly secured to a stub shaft 56 rigidly secured to a lower roller 57. The belts are so arranged that the rollers 41 and 57 are rotating in opposite directions, thereby causing the same to be twisted or rotated in situ. The pulley 53 is rigidly secured to a shaft 58, which shaft in turn is rigidly secured to the roller 59, whereby roller 59 is driven and acts to retract the mandrel 12 whenever the parts are in the position shown in Figure 4. A coacting roller 60 is arranged directly below roller 59 and is supported in the desired position in the framework 61 by an adjustable screw 62. The shaft 63 carries at its end suitable blocks 64 adapted to support the springs 65, which in turn support the bearing blocks 66 of shaft 58. The shaft 58 extends beyond the bearing blocks 66 and has the eyes 68 of chains 69 fitted thereover, so that when these rods are pulled downwardly shaft 58 and associated parts are pulled downwardly. Chains 69, as shown in Figure 1, are connected to a cross bar 70 which in turn is connected to a pull rod 71, and pull rod 71 at its lower end is pivotally connected with treadle 7. It will thus be seen that when treadle 7 is forced downwardly by the foot of the operator shaft 58 will be pulled downwardly and roller 59 will be pressed against the mandrel 12, and as this roller is rotating the mandrel will be gradually retracted or moved toward the supporting bracket or standard 72. As soon as the rope 10 has been placed in the position shown in Figure 7, treadle 7 is depressed and the rope quickly wound around the mandrel, as shown in Figure 8. The treadle 7 is maintained depressed, so that the mandrel will be gradually withdrawn and as it is gradually withdrawn the rollers 41 and 57 will rotate the grommet and gradually twist the free part of the rope 10 around the looped part, so that by the time the mandrel reaches the position shown in Figure 9, the grommet will be completely formed, except that the free end or extension 8" will be hanging loose. At a later time this is forced beneath one of the twists 8' and then the extra portion cut off. When other strands of rope are looped over the knob 9, as heretofore described, and treadle 6 is depressed, roller 40 will be elevated so as to press the mandrel against roller 41. This will cause the roller 41 to move the mandrel 12 outwardly to its outer position with the stop 43 resting against abutment 44. By the time the mandrel has been moved outwardly the new rope 10 will have been twisted and may then be manually looped around the mandrel, as shown in Figure 7, ready for a second operation. This action is continued as long as the machine is in operation, whereby suitable grommets are formed.

What we claim is:—

1. A grommet forming machine, comprising

ing a twisting mechanism for twisting strands into a rope, a reciprocating and partly rotating mandrel positioned to receive the twisted strands, means including a roller for 5 moving the mandrel in one direction, a pair of twisting rollers coacting with the mandrel for twisting said twisted strands so as to form a round grommet, and a foot operated mechanism for moving said mandrel so that 10 one of the twisting rollers will propel the mandrel to an outer position ready for a second grommet.

2. A grommet forming machine, comprising a twisting mechanism for twisting several 15 strands into a rope, a mandrel adapted to receive said rope, a pair of twisting rollers coacting with said mandrel for twisting said rope into a round grommet, means for moving said mandrel in one direction after said twisting rollers form said grommet, and a foot operated mechanism for raising said mandrel to engage one of said twisting rollers after said 20 grommet has been formed, whereby said last-mentioned twisting roller will move said mandrel to an outer position.

3. A grommet forming machine, including means for twisting a rope into a ring presenting a grommet and means for twisting rope strands into a rope formation, said last-mentioned means including a rotatable knob, power operated means for rotating the knob, a clutch, a spring for throwing the clutch into operation, and manually actuated means for moving said spring to a non-functioning position.

4. A grommet making machine, including a twisting apparatus and means for turning the twisted rope into a ring grommet, said twisting apparatus being formed with a knob over 40 which the strands of rope are looped preparatory to twisting, a shaft carrying said knob, a pulley loosely mounted on said shaft, a clutch member rigidly secured to said shaft, a spring for pressing said pulley against the clutch member, a second spring stronger than the first spring for preventing the first spring from functioning, a power cable coacting with said pulley for rotating the same, and foot operated means for moving the second- 45 mentioned spring to a non-functioning position, whereby the first-mentioned spring will cause the pulley to engage the clutch member and be rotated thereby.

5. In a grommet forming machine, a twisting structure, a treadle operated mechanism for connecting power to the twisting structure, a forming mandrel, a roller for raising said mandrel, means carrying the roller operated by said treadle, whereby said mandrel 55 will be raised when the power is connected to said twisting structure, means acting on said mandrel when the same is raised for

forcing the same to an outer position, power driven means for forcing said mandrel inwardly, and a pair of twisting rollers mounted adjacent said mandrel for forming a grommet from a twisted rope as the mandrel is moved to an inner position.

6. In a grommet forming machine, a reciprocating mandrel, a pair of power operated twisting rollers, means for forcing the mandrel against one of the rollers for causing the mandrel to be moved to an outer position, a power operated roller for moving the mandrel to an inner position, and means for holding the mandrel in a central position between the twisting rollers as the mandrel is moved to an inner position, whereby a rope looped over the mandrel will be twisted by said twisting rollers and thereby formed into a grommet.

7. A grommet forming machine, including a mandrel having a bore extending therethrough with means presenting a square opening at one end, said opening being slightly twisted, a square shaft extending through said opening into the mandrel, one end of said shaft being fixed against rotation, said shaft being twisted, whereby as said mandrel moves back and forth it will rotate to the extent of the twist in said shaft, power driven means for moving said mandrel in one direction, and power driven twisting rollers positioned to twist a rope into a grommet as the first-mentioned power driven means moves the mandrel in one direction, and a foot operated mechanism for causing the mandrel to engage one of the twisting rollers, whereby the mandrel is moved back to its starting point.

8. A grommet forming machine, including a reciprocating mandrel, a pair of twisting rollers coacting with said mandrel for twisting said rope into a grommet, a lifting roller for lifting said mandrel so that one of the twisting rollers will move the mandrel in one direction, a foot operated mechanism for lifting said lifting roller, and a power driven roller for moving the mandrel in the opposite direction and a foot operated mechanism for causing said power driven roller to function.

9. A grommet forming machine, including a forming mandrel adapted to receive a rope, a pair of twisting rollers coacting with the mandrel for twisting said rope into a grommet, a power driven roller for moving said mandrel as said twisting rollers function, a supporting roller for supporting said mandrel as it moves, a spring for normally holding the first-mentioned roller out of contact with the mandrel, and foot operated means for overcoming the action of said spring.
